UNITED STATES PATENT OFFICE.

MAURICE M. GLASSER, OF CHARLESTON, SOUTH CAROLINA.

FAN.

Application filed October 25, 1921. Serial No. 510,256.

To all whom it may concern:

Be it known that I, MAURICE M. GLASSER, a citizen of the United States, and a resident of Charleston, in the county of Charleston and State of South Carolina, have invented certain new and useful Improvements in Fans, of which the following is a specification.

My invention relates to motor operated 10 fans of that type embodied in my Patent No. 1,354,098 issued September 28, 1920, in which the rotating fan wheel continuously oscillates through a fixed arc and at the same time bodily rotates so that the path of the 15 arc continuously changes to effect a diffusion of the air current produced by the fan over a greater and constantly changing area.

The purpose of my present invention is the provision of a fan of the above described 20 character in which the mechanism for effecting the oscillation of the fan is adjustable to vary the length of the arc of oscillation.

Another purpose of the present invention is to provide a fan in which the mechanism 25 for effecting bodily rotation of the fan is adjustable to vary the degree of intermittent rotation, such mechanism also including means for preventing the accidental disengagement of the actuating lug from the 30 operating yoke so that the proper operation of the mechanism is at all times insured. Furthermore, my invention provides a clutch for preventing undue movement of the rotating mechanism so at each operation of 35 such mechanism the degree of rotary movement of the fan will be the same as long as the single adjustment of the mechanism is maintained.

A further object of my invention is to 40 provide a device of the character described in which means for effecting a bodily rotation of the fan include a ratchet wheel and a pawl co-acting therewith, such pawl being formed and actuated to obviate the "clicking" noise usually incident to the operation 45 of pawl and ratchet wheel arrangements.

I will describe one form of fan embodying my invention and will then point out the novel features thereof in claims.

50 In the accompanying drawings:

Figure 1 is a view showing in perspective one form of fan embodying my invention.

Figure 2 is a detailed perspective view of the oscillating mechanism comprised in the 55 fan shown in Figure 1 and embodying my invention.

Figure 3 is a horizontal sectional view taken on the line 3-3 of Figure 4.

Figure 4 is a fragmentary view showing in side elevation and partly in section the 60 frame and clutch mechanism shown in Figure 1.

Similar reference characters refer to similar parts in each of the several views.

Referring specifically to the drawings and 65 particularly to Figure 1, my invention in its present embodiment comprises a fan wheel W operated by a motor M which is supported for oscillatory movement by a yoke Y. The yoke Y in turn is adapted 70 to be suspended from a ceiling so as to be free to rotate about a vertical axis through the medium of an axle A which is adapted to be fixedly secured to the ceiling in any suitable manner. The yoke Y includes an 75 upper horizontal portion 15 and two vertical portions 16 and 16^a, the lower ends of which latter are provided with bearings 17 and 17^a, respectively, in which are journaled stub axles 18 and 18^a, respectively, for supporting the fan motor for oscillatory movement about a horizontal axis. The axle A extends through a bearing 19 formed in the horizontal portion 15 so that with the yoke secured against displacement from the axle 80 it is free to rotate about the axle as a center.

The oscillatory movement of the motor M within the yoke Y is effected by a mechanism which as illustrated to advantage in Figure 85 2 includes the motor shaft 20 operatively connected to a counter shaft 21 through the medium of a worm and worm wheel arrangement, indicated at 22, all of which are enclosed in a suitable housing 23 (Figure 1). By this arrangement the shaft 21 90 will be driven at an appropriately reduced speed as compared with the speed of the motor shaft 20. One end of the shaft 21 projects from the housing 23 and is there provided with a disc 24 removably fitted 95 thereon by a collar 25 and a set screw 26. The disc 24 is formed with an arcuate slot 27 that is arranged spirally of the axis of the vehicle, and mounted within this slot is a bolt or pin 28 to which is pivotally connected one end of a link 29. The opposite 100 end of the link 29 is pivotally connected to a bolt 30 extending into an arcuate slot 31 formed in one arm 32 of a plate P. As shown in Figure 1 this plate P includes another arm 33 disposed at right angles to the arm 32 and provided with a slot 34 through

105

110

which extends a pair of bolts 35 for securing the plate as a unit to the portion 16^a of the yoke Y.

The bolts 28 and 30 are provided with nuts 28^a and 30^a, respectively, which function not only to secure the link in operative connection with the plate P and the disc 24, but to permit an adjustment of the bolts along the length of the slots 27 and 31 and to lock the same in adjusted position. The bolts 35 in conjunction with the slot 34 permit of a vertical adjustment of the plate P upon the yoke Y. By virtue of these adjustments, the position of the link 29 with respect to the disc 24 can be changed so as to vary not the degree of oscillation of the motor M, but the termini of the arc of oscillation with respect to the axles 18 and 18^a. That is to say, the link 29 when in normal position effects an oscillation of the motor say 30° to each side of the axles 18 and 18^a, whereas when the link has been adjusted the greatest degree of which it is possible, the motor oscillates through a path of 60° at one side of the axles 18 and 18^a. It will of course be understood that by changing the plate P to the opposite edge of the portion 16^a of the yoke, and reversing the position of the disc 24 on the shaft 21, this maximum adjustment of the link 29 will effect the oscillation of the motor through a path of 60° to the opposite side of the axles 18 and 18^a.

As illustrated to advantage in Figure 4, the lower end of the axle A is provided with a reduced extension 36 on which is pivotally mounted an arm 37, such arm being confined on the extension by means of a nut 38. The arm 37 carries at its free end a pawl 39 pivotally mounted on the arm by means of a screw 40. This pawl 39 is adapted to engage at times the teeth of a ratchet wheel 41 mounted on the extension 36 and having all of the teeth thereof extending in the same direction. The pawl 39 carries a depending pin 42 which is connected to one end of a spring 43, the opposite end of the latter being connected to the arm 37 whereby the spring is caused to normally urge the pawl into engagement with the teeth of the ratchet wheel 41. It is desirable that means be provided to prevent the occasioning of noise ordinarily incident to the operation of pawl and ratchet wheel arrangements, which noise is caused by the contact of the pawl with successive teeth of the ratchet wheel as the pawl slides along such teeth. To this end, the pawl 39 is formed to include an integral tail piece portion 39^a, which tail piece extends substantially at right angles to the pawl body, whereby the complete pawl has substantially the form of a bell crank, as shown. The tail-piece portion of the pawl carries adjacent to its free end a depending lug

or pin 44 which is adapted to be engaged by bolts 45 adjustably secured in slots 46 formed in a T-shaped plate 47. The arm 37 is provided with an upstanding lug or pin 37^a adjacent both to its free end and to the side thereof opposite that nearest to the forward portion of the pawl, which lug or pin 37^a serves as a stop for contacting the tail-piece portion 39^a to limit the movement of the pawl in one direction about its pivot. The plate 47 is secured to the casing of the motor M by means of bolts or rivets 48 as is clearly shown in Figure 1. One of the bolts 45 carries a fork-shaped member 49 which is slidably fitted on the bolt and adapted to be locked in any adjusted position by means of a set screw 50. The forked end of the member 49 embraces a relatively large set screw 51 fitted within a plate 52 secured to the housing 23.

The foregoing elements constitute the mechanism for effecting rotary movement of the yoke Y and consequently the motor M, the adjustability of the bolts 45 permitting of a variance in the intermittent rotating movement of the motor. The member 49 is designed to prevent accidental displacement of the lug 44 from between the bolts 45 so that it will at all times be disposed in the path of movement of the bolts, and thereby insuring of the proper operation of the pin 44 and the pawl 39.

The ratchet wheel 41 is operatively connected to the yoke Y to effect intermittent rotation of the latter under the action of the pawl 39, through the medium of a clutch designated generally at K. This clutch in the present instance comprises a disc 53 secured to the upper side of the ratchet wheel by means of screws 54, and a second disc 55 super-imposed on the first disc, and with both of the discs surrounding the lower end of the axle A. The upper disc 55 is urged toward the lower disc 53 by springs 56 mounted in pockets 57 formed in a portion 15 of the yoke. The springs are confined in the pockets and the tension thereof may be varied by means of screw plugs 58 threadedly fitted in the pockets 57 whereby the friction between the discs can be varied.

The operation of the fan is as follows: current is supplied to the motor M through wires and collector rings, the latter being preferably arranged in the manner shown in Figure 1, and with the motor energized rotation of the fan wheel W is effected. With the rotation of the motor shaft 20, rotation of the disc 24 is effected, and under the action of the pivoted link 29 oscillation of the motor M is effected about the stub axles 18 and 18^a as a center. This obviously causes an oscillation of the fan wheel through a fixed arc, while at the same time the wheel itself rotates about the 130

motor shaft as a center. During oscillation of the motor M, a corresponding movement is imparted to the bolts 45 thus causing the latter to alternately engage the lug 44 carried by the pawl and to thereby effect an oscillatory movement of the arm 37. When the lug or pin 44 is engaged by one of the bolts 45, as illustrated in Figure 1, the pawl 39 will be held in engagement with the teeth of the ratchet wheel and the latter will be rotated. The other bolt 45 will engage the lug 44 to move the pawl 39 about its pivot and out of engagement with the teeth of the ratchet wheel, whereby movement of the pawl relatively to the ratchet wheel will not be attended by any objectionable noise, such as the "clicking" sounds caused by a pawl sliding over ratchet teeth. Moreover the wear on the co-engaging surfaces of the pawl and ratchet teeth is reduced to a minimum and the further movement of the arm 37 under the control of the last named bolt 45 is not resisted by friction resulting from a sliding engagement of the pawl with the ratchet teeth. The stop 37^a limits the movement of the pawl about its pivot when actuated by the last named bolt 45 and prevents the lug 44 from being moved out of position to be engaged by the bolts 45 successively. It will thus be apparent that an intermittent rotation of the ratchet wheel 41 is effected. The discs 53 and 55 provide frictional contact sufficient to form an operative connection between the yoke Y and the ratchet wheel 41 so that under the intermittent movement of the latter a corresponding movement of the yoke is effected. This obviously causes an intermittent rotation of the motor M about the vertical axis without interfering with the oscillatory movement about the horizontal axis. By a proper adjustment of the screw plugs 58 friction can be set up between the discs of the clutch 40 sufficient to provide an operative connection between the ratchet wheel and yoke and at the same time to prevent excessive movement of the wheel or yoke under the action of the pawl 39 so that each intermittent 45 rotative movement of the motor can be of a predetermined distance thus rendering this rotating movement uniform and irrespective of the speed with which the motor M oscillates.

55 Although I have herein shown and described only one form of fan embodied in my invention, it is to be understood that various changes and modifications may be made herein without departing from the spirit of the invention or the spirit and scope of the appended claims.

What I claim is:

1. A fan comprising a fan wheel having supporting and driving means therefor operating to bodily oscillate the fan wheel in

one plane and to bodily rotate the same in another plane in a step by step movement, and means for damping the bodily rotational movements of the fan wheel in said step by step movement. 70

2. A fan comprising a fan wheel having supporting and driving means therefor operating to bodily oscillate the fan wheel in one plane and to bodily rotate the same in another plane in a step by step movement, 75 said means being adjustable to vary the arc of oscillation with relation to the axis of oscillation and to vary the step by step movement.

3. A fan comprising a fan wheel having supporting and driving means therefor operating to bodily oscillate the fan wheel in one plane and to bodily rotate the same in another plane in a step by step movement, 80 said means being adjustable to increase or decrease the step by step movement.

4. A fan comprising a fan wheel, a motor for supporting and driving the fan wheel mounted for rotation about a horizontal axis and a vertical axis, mechanism operating to 90 oscillate the motor about the horizontal axis, mechanism operable by the oscillation of the motor to effect a step by step rotational movement of the motor about the vertical axis, the last means being adjustable to increase or decrease the distance of each step 95 by step movement.

5. A fan comprising a yoke, a motor mounted for oscillatory movement within the yoke, a fan wheel connected to the motor shaft, and mechanism for oscillating the motor comprising a counter shaft operatively connected to the motor shaft, a disc 100 fixed to the counter shaft and having a spirally arranged slot formed therein, a plate 105 secured to the yoke for vertical adjustment and having an arcuate slot formed therein, bolts adjustable within the slots of the disc and plate, and a link pivotally connected to the bolts. 110

6. A fan comprising an axle, a yoke rotatably mounted on the axle, a motor mounted for oscillatory movement within the yoke, a fan wheel operatively connected to the motor, mechanism operable by the motor for oscillating the latter, and mechanism for intermittently rotating the yoke about the axle as a center, said mechanism comprising a ratchet wheel mounted on the axle and operatively connected to the yoke, an arm pivoted on the axle, a spring pressed pawl pivoted intermediately on the arm and adapted at its forward end to engage the ratchet wheel, a lug carried by the pawl at its rearward end, and means carried by the motor and operable under the oscillatory movement of the motor to engage said lug to cause said pawl to rotate the ratchet wheel and to move the pawl about its pivot out of engagement with the ratchet wheel, alternately. 125 130

7. A fan comprising an axle, a yoke rotatably mounted on the axle, a motor mounted for oscillatory movement within the yoke, a fan wheel operatively connected to the motor, mechanism operable by the motor for oscillating the latter, and mechanism for intermittently rotating the yoke about the axle as a center, comprising pawl and ratchet means, a disc clutch operatively connecting said means to the yoke which is adjustable to vary the friction between the discs, and means operable by the oscillation of the motor for actuating the pawl and ratchet means.

5 10 15 20 25

8. A fan comprising an axle, a yoke rotatably mounted on the axle, a motor mounted for oscillatory movement within the yoke, a fan wheel operatively connected to the mo-

tor, mechanism operable by the motor for oscillating the latter, and mechanism for intermittently rotating the yoke about the axle 30 as a center, comprising pawl and ratchet means, a disc clutch operatively connecting said means to the yoke which is adjustable to vary the friction between the discs, and means operable by the oscillation of the 35 motor for actuating the pawl and ratchet means.

9. A fan comprising an axle, a yoke rotatably mounted on the axle, a motor mounted for oscillatory movement within the yoke, a 40 fan wheel operatively connected to the motor, mechanism operable by the motor for oscillating the latter, and mechanism for intermittently rotating the yoke about the axle 45 as a center comprising pawl and ratchet means, a disc clutch operatively connecting said means to the yoke which is adjustable to vary the friction between the discs, and means operable by the oscillation of the motor for actuating the pawl and ratchet 50 means, said last means being adjustable to vary the degree of movement of the pawl and ratchet means.

MAURICE M. GLASSER.
